UNITED STATES PATENT OFFICE.

DAVID S. COOK, OF COLUMBUS, OHIO.

CAR-DOOR.

SPECIFICATION forming part of Letters Patent No. 423,739, dated March 18, 1890.

Application filed March 8, 1889. Renewed February 21, 1890. Serial No. 341,287. (No model.)

To all whom it may concern:

Be it known that I, DAVID S. COOK, a citizen of the United States, residing at Columbus, in the county of Franklin and State of Ohio, have invented a certain new and useful Improvement in Car-Doors, of which the following is a specification.

My invention relates to the improvement of freight or box car doors; and the objects of my invention are to so connect the door with the car or support it therefrom as to admit of its being closed into the door-frame until its outer surface is flush with the outer side of the car, to provide the car and door with means whereby the door may be closed into the frame by leverage-power, to obviate the use of a lower door-track on the outer side of the car, to so support said door when open as to prevent its binding against the car, to readily and easily open and close the door, and to accomplish these objects in a simple and inexpensive manner. These objects I accomplish in the manner illustrated in the accompanying drawings, in which—

Figure 1 is a side elevation of a portion of a car, showing the door closed. Fig. 2 is a horizontal section taken on line $x-x$ of Fig. 1. Fig. 3 is a vertical section taken on line $y-y$ of Fig. 1, showing the door open and in position for closing. Fig. 4 is a similar sectional view showing the door closed, and Fig. 5 is an inner side view of the door-frame and door.

Similar letters refer to similar parts throughout the several views.

a represents a car, the frame-work of which is of the usual form.

b b' represent the usual vertical door-frame posts, and c the longitudinal beam passing over said posts, and forming the upper side of the door-frame, formed in the usual manner.

d represents a horizontal section of the track-bar supported from the outer side of the car in a line above and to one side of the doorway.

d' represents a second section of the track-bar, the inner end of which is horizontally opposite and in line with the inner end of the track d , although a short distance therefrom. The track d' is inclined inward from said inner end, and has its outer end meeting the face of the car at a point opposite the

inner side of the frame-post b' . These track-sections are connected with the side of the car by means of supporting-arms e . Extending between the opposite inner ends of these track-sections and the car-siding are horizontal arms e' , each provided with a central slot e^2 . Extending between these arms e' , and having its ends resting and adapted to slide within the slots e^2 , is a short bar f . This bar f is provided on its rear side with a lug f' , and has secured to or formed on its front side a short section of track-bar g , said section being of such length as, when the bar f is in the front ends of the slots e^2 , to fill the greater portion of the space between the inner ends of the track-sections d d' , thus forming a detached continuation of the latter.

Pivotedly secured to the lug f' of the sliding bar f is the slotted upper end of an arm h , the remaining end of which is rigidly secured to a horizontal rod i , projecting from the inner side of the door-frame post b , through which it passes loosely.

k represents the door, which is of the ordinary form. Secured to the outer side of the door k , at the upper end thereof, are the lower portions of two upwardly-extending hangers l , consisting of metallic bars bent outwardly from the face of the door, thence upwardly, inwardly, and again downwardly to form hooks, which engage, when the door is open, with the track-section d , and support the door therefrom in the position shown in the dotted lines of Fig. 1 of the drawings.

Supported, as shown, from the inner side of the door k , near the lower end thereof, and parallel with the inner face thereof, is a track-bar n . This track-bar n is adapted to rest and slide within a metallic block m , so shaped as to partially embrace said track, and having projecting from its rear side a lug, to which is pivotally secured the slotted end of a short arm p , which has its remaining end rigidly connected with one end of a horizontal rod q within a depression or mortise q' , formed within the front and inner side faces of the frame-post b . This rod q , passing loosely through said post b , has its remaining end rigidly secured to an arm r , extending inward at an angle with the position of the arm p . The inner end of the rod i is, as de-

scribed for the rod *q*, rigidly connected with one end of an arm *s*, which extends inward and at an angle with the position of the arm *h*.

The free ends of the arms *s* and *r* are pivotally connected with an approximately vertical rod *t*, which, passing downward through an opening in the floor of the car, is pivotally connected beneath the car with a lever *u*, the rear end of which is pivotally connected with 10 a pin *v*, made to project outwardly from the lower frame-work of the car.

w represents a short metallic strap or bar, having one of its ends secured to the outer side of the car at a point opposite the post *b*', 15 and near the lower portion of the doorway, the remaining end of said bar being made to project outward a short distance over said doorway.

The operation of my device is as follows: 20 The door being open, it is supported upon the track-section *d*, said track-section being supported at such distance from the car as to prevent the contact of the door therewith. The door is further assured in its position 25 by having its inner and lower track *n* supported within the block *m*, which is supported, as hereinbefore described, in front of a depression or mortise *q'* of the frame-post *b*. It being desired to close the door, the latter 30 is pushed forward until the hanger *l* nearest the doorway has passed over the movable track-section *g* and over the section *d'* until the remaining hanger *l* is upon the movable section *g* and the door is opposite the doorway. Owing to the incline of the track-bar 35 *d'*, it will be seen that when the door is opposite the doorway that side of the door nearest the frame-post *b*' will be drawn inward sufficiently to allow it to pass behind the projecting end of the strap *w*. By pressing downward upon the lever *u* the rod *t* will be made 40 to descend, which movement, through the arm *s*, rod *i*, and arm *h*, and the connection of the latter with the movable track *g*, will operate 45 to draw said movable track-section and the door supported thereon inward, said door entering the door-frame, which is cut away about its outer side to receive said door until the latter is flush with the car-siding. A recess *y* 50 is formed in the front side of the horizontal beam to receive the arm *h* and lug *f'*. The above-described downward movement of the rod *t* will also operate, through the arm *h*, rod *q*, arm *p*, and the connection of the latter with the block *m*, to force inward the lower 55 part of the door. It will be seen that any tendency of the door to be elevated when drawn inward will be obviated by having the pivot-pins which connect the track-sections *g* and arm *h* and block *m* and arm *p* passing 60 through slots formed in said arms *h* and *p*. The door may be opened by pressing upward 65 on the lever *u* until the door is forced outward to the position shown in Fig. 3 of the drawings, when it may be pushed back to its

position upon the bar *d*, as hereinbefore described.

By the above-described construction it will be seen that the door will be so supported as to prevent its binding against the car.

It is well known that door-tracks supported along the lower portion of the car-siding often become bent or broken, from contact with wagons or passing cars, and thus prevent the opening or closing of the door. This difficulty, it will readily be seen, will be obviated by the construction herein described, wherein no outward projections appear on the lower portion of the car.

I am aware that inclined door-tracks have 80 been used heretofore, and therefore do not claim, broadly, such incline.

Having now fully described my invention, what I claim, and desire to secure by Letters Patent, is—

1. The combination, with the car, horizontal track-section *d*, and inclined track-section *d'*, supported from said car, and intervening movable section *g*, supported in slotted arms *e'*, of the door *k*, supported by hangers *l*, and 90 made to slide on said track-section, substantially as and for the purpose specified.

2. The combination, with a car and its frame-work, the latter having recess *y*, and having supported therefrom horizontal track-section *d*, inclined section *d'*, and movable track-section *g*, supported in slotted arms *e'*, and door *k*, having hangers *l*, made to engage with and slide on said track-sections, of the slotted arm *h*, pivotally connected with said movable track-section, arm *s*, rigidly connected with arm *h* by rod *i*, approximately vertical rod *t*, having its upper end pivoted to said arm *s*, and having its lower end projecting through the car-floor and pivotally connected with lever *u*, the latter also pivoted to the car frame-work, substantially as and for the purpose set forth.

3. The combination, with a car and its frame-work, the latter having recesses *y* and *q'*, and having supported therefrom horizontal track-section *d*, inclined section *d'*, movable section *g*, supported and adapted to slide in arms *e'*, door *k*, having hangers *l*, supported and adapted to slide on said track-sections, track-bar *n*, supported from the inner side of said door, slotted arm *h*, pivotally connecting with movable track-section *g*, arm *s*, connected by rod *i* with arm *h*, track guide-block *m*, slotted arm *p*, pivotally connected with said block, arm *r*, connected with arm *p* by rod *q*, and approximately vertical rod *t*, pivotally connected with arms *s* and *r* and passing downward through the car-floor, and lever *u*, pivotally connected with said rod *t* and the car frame-work, substantially as and for the purpose set forth.

DAVID S. COOK.
